UNITED STATES PATENT OFFICE.

ALBERT G. BIERBACH, OF MILWAUKEE, WISCONSIN.

ADJUSTABLE DOOR-HANGER.

SPECIFICATION forming part of Letters Patent No. 642,069, dated January 30, 1900.

Application filed July 17, 1897. Serial No. 644,940. (No model.)

To all whom it may concern:

Be it known that I, ALBERT G. BIERBACH, a citizen of the United States, residing at Milwaukee, in the county of Milwaukee and State 5 of Wisconsin, have invented new and useful Improvements in Adjustable Door-Hangers, of which the following is a specification.

My invention relates to improvements in adjustable door-hangers.

10 The objects of my invention are, first, to provide means for adjusting a door both vertically and laterally, and, second, to provide means for easily removing the door from its hangers.

15 In the following description reference is had to the accompanying drawings, in which—

Figure 1 is a front view of a portion of the door with its supporting-track and one of my improved hangers, two of such hangers being 20 required with each door. Fig. 2 is a vertical section view of the device shown in Fig. 1, drawn at right angles thereto. Fig. 3 is a detail view of the rear side of one of the hangers as it appears upon the door, showing the 25 projecting end of the adjusting-bolt. Figs. 4 and 5 are detail front and side views, respectively, of a modification of the lower hanger-section, whereby the door is made readily detachable from the main portion of the hanger.

30 Like parts are identified by the same reference-letters throughout the several views.

The door A is provided with two brackets B, one of which only is shown and described. The bracket B is provided with an adjusting-bolt C, which operates in smooth bearings 35 formed in the vertical walls of said bracket. The adjusting-bolt C is threaded at its center and passes through a screw-threaded eye in the lower end of the section D of the hanger-bar, the hanger being adjusted transversely 40 of the door by turning the bolt C. The upper end of the section D is provided with a screw-threaded socket E, in which the upper section F of the hanger-bar, which is also 45 screw-threaded, operates, the latter being swiveled to the frame G of the truck. The frame G is supported by the overhead track H. The hanger is adjusted to raise or lower the door by applying a wrench to the nut I 50 of the upper hanger-section F.

In Figs. 4 and 5 I have shown a convenient device for facilitating the removal of the door without unscrewing the hanger, which con-

sists in forming the lower hanger-section D in two parts, which are connected together 55 by interlocking hooks L and L'. With this construction the door may be readily removed by disengaging the hooks.

It is obvious that by the combination of the two adjusting devices described the door is 60 susceptible of four adjustments upon its hangers—viz., upward and downward and toward the right or left—whereby the single object or unitary result of bringing the door to and retaining it at the exact point of adjustment 65 desired is readily attained.

Having thus described my invention, what I claim as new, and desire to secure by Letters Patent, is—

1. In a door-hanger, the combination of a 70 bracket adapted to be attached to the upper edge of a door; an adjusting-bolt arranged transversely through the upper projecting walls or lugs of said bracket, having smooth bearings at each end thereof in said walls, 75 and provided with a central screw-threaded portion between said walls; a hanger-bar provided with a screw-threaded eye operating upon the central screw-threaded portion of 80 said adjusting-bolt, substantially as described.

2. In a door-hanger, the combination of a bracket adapted to be attached to the upper edge of a door; an adjusting-bolt arranged 85 transversely through the upper projecting walls or lugs of said bracket, having smooth bearings at each end thereof in said walls, and provided with a central screw-threaded portion between said walls; a vertical hanger-bar formed in two parts, having the lower 90 end of the lower part provided with a horizontal screw-threaded eye operating upon the central screw-threaded portion of said adjusting-bolt, and its upper end provided with a screw-threaded socket operating upon the 95 screw-threaded lower end of the upper section or part of the hanger, the latter being swiveled to a supporting bracket or carriage, all substantially as and for the purpose specified. 100

In testimony whereof I affix my signature in the presence of two witnesses.

ALBERT G. BIERBACH.
